CLAIM

What is claimed is the ornamental design for a cantilever toolbox, as shown and described.

DESCRIPTION

FIG. 1 is a perspective view of the cantilever toolbox at closed position, with the handle at vertical position and with the lid closed;

FIG. 2 is a perspective view of the cantilever toolbox seen in FIG. 1 at closed position, with the handle at horizontal position and with the lid closed;

FIG. 3 is a front view of the cantilever toolbox seen in FIG. 1 at closed position, with the handle at horizontal position and with the lid closed;

FIG. 4 is a right side view of the cantilever toolbox seen in FIG. 1 at closed position, with the handle at horizontal position and with the lid closed; left side view being a mirror image;

FIG. 5 is a top view of the cantilever toolbox seen in FIG. 1 at closed position and, the handle at horizontal position and with the lid closed;

FIG. 6 is a front perspective view of the cantilever toolbox at an opened position, with the handle at vertical position and with the lid opened;

FIG. 7 is a right side view of the tool box seen in FIG. 1 at an opened position, with the handle at vertical position and with the lid opened;

FIG. 8 is top view of the tool box seen in FIG. 1 at an opened position, with the handle at vertical position and with the lid opened;

FIG. 9 is a rear perspective view of the cantilever toolbox at an opened position, with the handle at vertical position and with the lid closed; and,

FIG. 10 is a rear perspective view of the cantilever toolbox at an opened position, with the handle at vertical position with the lid opened.
